UNITED STATES PATENT OFFICE.

ARTHUR EMLEN BROWN, OF PHILADELPHIA, PENNSYLVANIA, ASSIGNOR TO BROWN
& BAILEY COMPANY, A CORPORATION OF PENNSYLVANIA.

DISPLAY BOX.

Application filed May 28, 1926. Serial No. 111,684.

An object of my invention is to provide an improved display box or carton which may be formed from a unitary piece or blank or suitable material, such as card-board, the blank being made by a suitable die and the parts of which may be folded or bent into proper relation or engagement to form the completed box.

A further object of my invention is to provide a display box which may be formed by folding a unitary blank of cardboard and which embodies means whereby the box may be easily and quickly set up.

A further object of my invention is to provide a foldable box with reinforced sides, front, back and bottom and therefore of a firm and not easily distorted construction.

My invention further includes all of the other various objects, operations and features of construction and arrangement hereinafter more definitely described or illustrated in the accompanying drawing.

Figure 1 is a plan view of the blank from which the box is formed, the points at which the blank is cut entirely through being indicated in full lines and those at which it is scored to facilitate the folding operation being indicated in dot and dash lines; Fig. 2 is a top plan view of the box; Fig. 3 is a transverse section on the line 3—3 of Fig. 2; Fig. 4 is a perspective view of the box in display position.

The blank is formed from a unit of cardboard or other suitable material by a die, the shape of the blank being shown in Fig. 1.

The box as set up has double sides, front, back and bottom, thus providing a firm construction and one which will not be easily distorted.

In the drawings, 1 and 2 are the outer and inner bottoms respectively, 3 and 4 the inner sides and 5 and 6 the outer sides. The double front comprises the outer panel 7 and inner panel 9 and the double back is formed of the outer and inner panels 8 and 10 respectively. The inner bottom 2 is made of less width than the outer bottom 1 for the purpose hereinafter described.

In forming the box from the blank the panels 7 and 8 are preferably first folded or bent at the scored lines 7' and 8' respectively, into positions at right angles to the bottom 1; the panel 9 is then folded about the scored line 9' to form the interior of the

front of the box, paralleling the outer panel 7; as the panel 9 is folded into position, the inner bottom 2 is folded about scored line 2' so that it will rest upon the outer bottom 1; the inner panel 10 is then folded about the scored line 10' into a position at right angles to the inner bottom 2 and paralleling the outer panel 8. The tongue members 11, 12, 13, 14, 15, 16, 17 and 18 are folded respectively about the scored lines 11', 12', 13', 14', 15', 16', 17', and 18' at right angles to the respective panels to which they are joined towards the interior of the box.

The outer sides 5 and 6 are folded about the scorings 5' and 6', respectively, into positions at right angles to the bottom of the box and the inner sides 3 and 4 are then folded about the scored lines 3' and 4', respectively, to form the inner sides of the box paralleling respectively the outer sides 5 and 6. In the folding of sides 3 and 5 the tongue members 11, 13 and 15, folded as aforesaid, are secured or locked therebetween and likewise in the folding of sides 4 and 6 the tongue members 12, 14 and 16 are enclosed and held thereby, the engagement between the tongue members and the adjacent sides serving to hold the box together. The inner bottom 2 being of less width than the outer bottom 1, after the folding operation has progressed to the stage described, rectangular recesses will be formed at each side of the inner bottom corresponding to the thickness thereof and extending from the outer side edges 19, 19 thereof to the inner sides 3 and 4 of the box. Projecting from the inner sides 3 and 4 are tabs or flaps 20, 20 which are preferably of the exact size of said rectangular recesses and after the parts of the box have been folded as above described the tabs 20, 20 are snapped into said rectangular recesses wherein they fit snugly and are not dislodged by the usual handling of the box.

The tight engagement of the tabs within the recesses forms a secure locking means to hold the box together. I am aware that heretofore tabs or flaps carried by side members of a box have been folded so as to lie upon the box bottom and that these have been held in place by the inside bottom resting thereupon but there is much difficulty in the folding of a box so made with consequent increased cost of labor and wast-

age due to the mutilation of the boxes in the folding operation. These difficulties and disadvantages I have overcome in my improved box.

- 5 A lid A is provided for the box which may extend over the top of the box in shipping and which, when the contents are displayed for sale, may be folded and inserted in the back of the box so as to extend upwardly 10 therefrom and make visible advertising matter displayed thereon. The lid comprises a panel 21 which may be bent about the scored line 21' to enable the lid to cover the top of the box in shipment. When the lid 15 is used for display purposes, the panel 21 is in alinement with the back panel 8 and the panel 22, containing the label or advertising matter, is bent about the scored line 22' into parallel relation with the panel 21; the tab 20 23 is then inserted between the inner end 10 and the outer end 8 whereby the panel 22 is maintained in its display position.

While I have herein described with considerable particularity a preferred embodiment of my invention I do not thereby desire or intend to specifically limit myself to the precise details of construction and arrangement of parts to which I have referred as the same may be modified and varied in 25 minor particulars from the forms shown in the drawings and herein described, without departing from the spirit and scope of the invention as defined in the appended claims.

Having thus described my invention, I

claim and desire to protect by Letters Patent of the United States:

1. A box formed from a unitary blank of foldable material and comprising double side, front, back and bottom panels, the inner bottom panel being of less width than the outer bottom panel to provide recesses adjacent the sides of the box, jointed extensions on the inner side panels fitting snugly within said recesses and a lid adapted to extend over the top of the box in closed position and to be folded and inserted between the back panels and extend upwardly therefrom when the box is in display position.

2. A box formed from a unitary blank of foldable material and comprising double side, front, back and bottom panels, the inner bottom panel being of less width than the outer bottom panel to provide recesses adjacent the sides of the box, jointed extensions on the inner side panels fitting snugly within said recesses, tongue members extending from each end of the front and back panels adapted to be inserted and held between the adjacent side panels and a lid adapted to extend over the top of the box in closed position and to be folded and inserted between the back panels and extend upwardly therefrom when the box is in display position.

In witness whereof I have hereunto set my hand this 21st day of May, 1926.

ARTHUR EMLEN BROWN.
